Cyrus W. Anderson

ATTORNEY.

UNITED STATES PATENT OFFICE.

ENOCH N. BROWN, OF CHELTENHAM TOWNSHIP, MONTGOMERY COUNTY, PENNSYLVANIA.

WASTE VALVE FOR SANITARY APPLIANCES.

Application filed October 7, 1925. Serial No. 60,952.

My invention relates to waste valves which are adapted for use in connection with sanitary appliances such as bath tubs, basins and the like.

5 The general object of the invention is to provide a novel construction of valve with means for opening and closing the same which is compact and in effect self-containing.

10 It is also an object of the invention to provide a valve which may be installed or placed in position in constructions already in use with a minimum of change or alteration.

15 Another object of the invention is to provide means located directly underneath the valve element for actuating the latter, the said means being actuated by means located directly above the said valve element.

20 A further object of the invention is to provide a waste valve for sanitary appliances in which the valve element is adapted to be supported upon levers located within 25 and near the top of the outlet to be controlled, which levers are adapted to be actuated for opening and closing the said valve by means associated with the said valve.

25 To these and other ends the invention comprehends the construction and arrangement of parts as hereinafter described in detail, particularly pointed out in the claims, and as illustrated in the drawing in which I have shown a convenient form of 35 mechanical embodiment of the said invention.

30 It will be understood that the invention is susceptible of embodiment in other forms of construction than that shown and that 40 changes in the details of construction may be made within the scope of the claims without departing from the principle thereof.

In the drawing:

45 Fig. 1 is a central vertical section through the upper end portion of a conduit provided with a valve structure embodying the invention, the said valve being in closed position;

Fig. 2 is a similar view with the valve in open position; 50

Fig. 3 is a transverse sectional view taken on the line 3—3 of Fig. 1;

Fig. 4 is a vertical sectional view through the valve structure alone taken on the line 4—4 of Fig. 1; 55

Fig. 5 is a top plan view of the valve in position for controlling the outlet of a bath tub or the like; and

Fig. 6 is a perspective view of one of the levers by means of which the valve element 60 of the structure is adapted to be opened and closed.

Referring to the drawing: 1 designates the upper portion of a soil pipe leading from a bath tub or other structure, a portion of 65 the bottom of which is indicated at 2. The upper end of the soil pipe 1 is provided with a laterally extending flange 3 which is located underneath and in adjacent relation to the under side of a portion of the 70 part 2 of the bath tub or other appliance surrounding an opening 4 therein. The upper end of the soil pipe 1 and the flange 3 are clamped against a washer 5 underneath the portion of the bottom 2 surrounding 75 the opening 4 by means of a screw threaded coupling device or member 6 having a flange 7 which overlies the inner edge portion of the part 2 surrounding the opening 4. The coupling of the upper end of a 80 waste or soil pipe to a bath tub, basin or the like in this manner is quite well known.

The inner upper edge of the securing and coupling member 6 is beveled, as indicated at 85 10, to form a seat for the outer beveled edge of a valve 11. Bars 12 are connected at intervals at their upper ends to the valve 11 near its outer edge. These bars extend downwardly into the coupling member 6 and are engaged at their lower ends by a ring member 13. The valve 11, bars 12 and ring member 13 may be formed integrally, or the said bars may be rigidly connected in any other preferred manner.

A couple of downwardly extending projections 95 15 are secured to the lower end of

the coupling member 6 in diametrical relation with respect to each other. The lower ends of these projections are connected by a bar 16. The said projections and bar 16 may be formed integrally with each other and may be also formed integrally with the member 6, or they may be otherwise connected, as may be preferred. The bar 16 is provided with upwardly extending projections 17 spaced apart, as indicated, to form a guide for a head 18 upon the lower end of a manually operable member 19. The portion 19 of the said manually operable member is of reduced size as compared with the head 18 and extends upwardly through an opening 20 in the valve member 11. The head is provided with a slot, as indicated at 22, into which project the inner ends of levers 23 which levers extend outwardly between the projections 17, which are arranged in couples, and are mounted upon pivots 25 through the said projections. The outer ends of the said levers terminate at points or positions underneath the ring member 13 previously referred to. The inner ends of the levers are notched, as indicated at 26, and overlap each other as shown in the drawing. These overlapped end portions are provided with slots 27 through which a pin 30 extends the opposite ends of which are secured in holes in the portions of the head 18 upon opposite sides of the slot 22.

The upper end portion of the manually operable device 19 is provided with a disk member 31 which operates to prevent accidental removal of the valve member 11 from its position upon the member 19, and also operates as means for rendering more convenient the manual operation of the said member 19 to operate the levers 23 to open and close the valve 11. When in open position the disk member 31 occupies a position within the depression 35 of the valve with its top surface flush with the top surface of the outer edge or rim portions of the said valve. As indicated in the drawing, the disk member 31 is detachable or removable from the stem member 19. Upon such removal the valve 11 may be removed thereby providing free access to the levers 23 and other parts of the structure which normally are underneath the valve in order that any repairs thereto may be facilitated.

By reason of such access the cleaning of the portion of the structure underneath the valve is also facilitated.

When the valve 11 is in open position as shown in Fig. 2, its tendency due to gravity is to close. Such closing is resisted not only by such back pressure as may be due to water or air, or both, within the waste pipe, but also by the weights of the manually operable member including the parts 18, 19 and 31 and the inner end portions of the

levers 23. It is apparent that the shorter the leverage between the points of contact of the outer ends of the levers 23 with the ring member 13 when the valve is in open position, the greater security will there be against accidental closing of the valve due to its weight. In order, therefore, to provide a construction in which when once opened the valve will remain open, I have located the pivots 25 for the levers 23 as near to the outer ends of the latter as seems to be practical. However, it will be understood that my invention is not limited to the particular place of location of the pivots 25. Practically, however, said pivots should be located as near to the outer ends of the levers 23 as may be possible.

It will be noted that the outer edge portions of the projections 17 serve as additional guides for guiding the opening and closing movements of the valve.

It will be seen that by my invention I have provided a valve structure which is compact and in which the valve and operative parts are all located practically within the open upper end of the waste pipe through which water is adapted to be discharged from a bath tub, basin or other sanitary appliance or fixture. By providing a structure with the parts thereof arranged in compact relation to each other and in the position as stated I am enabled to avoid the use of operating means at some point a distance from the valve, usually outside of the bath tub, basin or other fixture, and which usually involves operative mechanism more or less complicated in character.

Although I have described my invention as being employed in connection with sanitary appliances or fixtures it will be understood that it may be employed for any purpose and in connection with appliances or apparatus of any character for which it may be suited.

Having thus described my invention, what I claim and desire to secure by Letters Patent is:

1. In a waste valve structure, the combination of a valve, pivoted levers located underneath the said valve for operating the same, and means extending outwardly through said valve for actuating the said levers to operate the said valve.
2. In a waste valve structure, the combination of a valve for closing the outlet to a waste pipe, levers located underneath the said valve within the said waste pipe, stationary means for supporting said levers, means whereby said levers are adapted to support the said valve, and means having connection with said levers and projecting from said pipe for actuating the levers to open and close the said valve.
3. In a waste valve structure, the combination of a valve, levers mounted within the

- 5 said pipe upon stationary pivots, said levers extending diametrically of the said pipe, means whereby the outer ends of said levers operate to support the said valve, means for actuating the said levers, said means having connection with the inner ends of said levers, and means exteriorly of the said valve for operating the said last mentioned means to open and close the said valve.
- 10 4. In a waste valve structure, the combination of a valve for opening and closing the inlet to a waste pipe, means within the said waste pipe adjacent the end thereof for operating said valve to open and close the same, means for actuating the said valve operating means, which means extends outwardly through an opening through the said valve and terminates in adjacent relation thereto, and means for guiding the inner end of said last mentioned means as the same moves back and forth relatively to the said valve.
- 15 5. In a valve structure for closing waste pipes, the combination of a valve, a bar supported within the said waste pipe near its inlet opening and extending transversely thereof, spaced projections extending upwardly from said bar, levers mounted upon said projections the outer ends of which extend beyond said projections to positions underneath the outer edge portion of the said valve, means whereby said valve is adapted to be supported upon the said outer ends, a member extending through the opening in said valve, said member being located between and guided by the said projections, means for connecting said member to the inner ends of said levers, and the outer end of said member projecting above the said valve whereby it is adapted to be operated to actuate the said levers to open or close the said valve.
- 20 6. In combination, a waste pipe for sanitary appliances, a coupling member for securing the upper end of said waste pipe to a member from which water is to be drained, the upper inner edge of which constitutes a valve seat, a valve for cooperating with said seat, said valve having a central opening extending therethrough, a bar within the said pipe and having connection at its opposite ends with the lower edge of the said coupling member, projections supported upon the said bar in spaced relation to each other, levers pivoted upon said projections the outer ends of which project beyond the outer edges of said projections, means whereby said valve is adapted to be supported by the outer ends of said levers, a manually operable member for actuating said levers, a pin and slot connection between the inner ends of said levers and the said manually operable member, the lower end of the said member being guided between the said projections, and the upper end portion of
- 25 said member extending outwardly through the opening in said valve, substantially as described.
7. In a valve structure of the character described, the combination of a valve having a central opening and also having inwardly extending bars secured at intervals to the outer edge portion thereof, and the inner ends of which bars are connected by a ring member, levers located inwardly of said valve, stationary pivots for supporting said levers intermediate their ends, the outer ends of said levers being located in position to contact with the said ring member and operating to support the same together with the said valve, and the inner ends of said levers overlapping each other, a manually operable member extending through the opening in said valve and having pin and slot connection with the inner ends of said levers, substantially as described.
- 30 8. In a valve structure for waste pipes, the combination of a tubular coupling member for coupling the inlet end of a waste pipe to the appliance from which water is to be drained, the inner upper edge of said coupling member constituting a valve seat, a valve adapted to cooperate with said seat, said valve having a central opening therethrough and also having bars connected at intervals to the outer edge portions thereof, which bars extend inwardly and are adapted to be guided by the said coupling member, a ring member connecting the inner ends of the said bars, a bar having connection at its opposite ends with the inner edge of the said coupling member, which bar is provided with outwardly extending projections in spaced relation to each other, levers pivoted intermediate their ends to the said projections, the outer ends of which levers project beyond the said projections and contact with the said ring member, and a manually operable member extending through the opening through said valve and having its inner portion guided between the said spaced projections, and means for pivotally connecting the inner portion of said member to the inner end portions of said levers whereby upon movement of the said manually operable member in one direction or the other actuation of the said levers is effected to cause opening or closing movement of the said valve.
- 35 9. A valve structure for controlling the outlet to a waste pipe, which comprises a valve, means located directly underneath said valve which is adapted to be moved to open and close said valve, and means having slidable connection with the said valve and pivotal connection with the said first named means for actuating the same to open and close the said valve.
- 40 10. A waste valve structure for closing the outlet to a waste pipe, comprising a valve,

means located underneath said valve within the adjacent end portion of the said waste pipe, and means having connection with the first named means and extending outwardly through the said valve for actuating the said means for opening and closing the said valve, and the said last named means being provided with a disk upon its outer end

which disk is adapted to be detached to permit removal of the said valve therefrom thereby permitting access to the said first named means.

In testimony that I claim the foregoing as my invention I have hereunto signed my name this 28th day of Sept., A. D., 1925.
